CLAIM

The ornamental design for a DC fast charger, as shown and described.

DESCRIPTION

FIG. 1 is a front elevation view of a DC fast charger
FIG. 2 is a left side elevation view of the DC fast charger of FIG. 1.

FIG. 3 is a rear elevation view of the DC fast charger of FIG. 1.

FIG. 4 is a right side elevation view of the DC fast charger of FIG. 1.

FIG. 5 is a top plan view of the DC fast charger of FIG. 1.

FIG. 6 is a left perspective view of the DC fast charger of FIG. 1; and,

FIG. 7 is a right perspective view of the DC fast charger of FIG. 1.

Features shown are of a DC fast charger. Broken lines included in the figures show portions of the DC fast charger that form no part of the claimed design.

1 Claim, 7 Drawing Sheets
